Inventor.

John Adams

United States Patent Office.

JOHN ADAMS, OF BIRMINGHAM, PENNSYLVANIA.

Design No. 4,257, dated July 26, 1870.

DESIGN FOR A TRADE-MARK.

The Schedule referred to in these Letters Patent and making part of the same

To all whom it may concern:

Be it known that I, JOHN ADAMS, of Birmingham, in the county of Allegheny and State of Pennsylvania, have invented and produced a new and original Design for a Trade-Mark, of which the following is a specification.

My design consists of a top or lid for a jelly-tumbler, having in the central portion of it a raised representation of a shoe and a fly, for the purpose of representing, by hieroglyphics, the words "shoe fly."

Near the outer edge of the lid are raised ornaments, clearly shown at *e e* and *f*, and at *h* is a raised scroll, with the words "trade-mark" in raised letters.

In the accompanying drawing, which forms part of my specification—

A represents the lid, and
B the jelly-tumbler.
O represents a shoe, and
D, a fly.
e e and *f* represent ornaments.

Claim.
I claim as of my invention—
The design for a trade - mark, as described and shown.

JOHN ADAMS.
